UNITED STATES PATENT OFFICE.

PHILIP LANG, OF CEDAR FALLS, IOWA, ASSIGNOR TO WAGNER MANUFACTURING COMPANY, OF CEDAR FALLS, IOWA.

DOOR LATCH.

Application filed September 24, 1925. Serial No. 58,368.

To all whom it may concern:

Be it known that I, PHILIP LANG, a citizen of the United States, of Cedar Falls, in the county of Black Hawk and State of Iowa, have invented certain new and useful Improvements in Door Latches; and I do hereby declare the following to be a full, clear, and exact description of the invention, such as will enable others skilled in the art to which it appertains to make and use the same.

My invention relates to improvements in door latches.

The object of my invention is to provide a door latch operated by a swinging handle, and the weight of the handle exerting pressure on the latch proper to hold the latch in either its latched or unlatched position.

Another object of my invention is to provide a latch of this character which will draw up the door tightly against the jam to form a tight joint therewith, and also providing means whereby the latch may be locked by an ordinary pad lock so that the lever can not be moved for unlatching the door.

A further object of my invention is to provide a latch of this character which can be readily applied to any sliding door and is reversible for a right and left hand door.

A still further object of my invention is to provide a simple, cheap and durable latch of this character having certain details of structure and combination of parts herein-after more fully set forth.

In the accompanying drawings:

Figure 1 is a side elevation of a portion of a door and jam showing my latch applied thereto, and in a latch position.

Figure 2 is a side elevation similar to Figure 1 showing the latch in an unlatched position.

Figure 3 is a transverse horizontal sectional view taken on the line 3—3 of Figure 1.

Figure 4 is a vertical longitudinal sectional view taken on the line 4—4 of Figure 1.

Referring now to the drawings, 1 represents the door and 2 the jam. Secured to the door by means of bolts 3, is the plate 4, said plate being of a rectangular elongated form and having an outwardly depressed central portion 5 intermediate its upper and lower ends. This depressed por-

tion 5 has riveted at the center the outwardly extending stub shaft 6, which extends through an opening 7 in the latch 8, whereby the latch is pivotally mounted thereon to swing in operative or inoperative position. The latch 8 has the hooked outer end 9 which is adapted to cooperate with the keeper 10. The hooked end 9, of the latch, has its inner wall 11 slightly tapered so as to cooperate with the curved wall 12 of the opening 13, of the keeper. Pivotally mounted upon the outer end of the stub shaft 6 is a plate 14, preferably of a circular form, and the stub shaft is riveted as indicated at 15, into the recess 16, in the outer face of the plate, whereby the disk is free to rotate on the stub shaft 6.

The latch 8 proper is provided with a slot having a radially extending portion 17, terminating in the segmental portion 18. The inner face of the plate 14 is provided with an inwardly extending pin 19 working in the segmental slot 18. The outer face of the plate 14 is provided with the two outwardly extending ears 20 and 21 having a pin 22 extending across the space between the ears and riveted thereto. Pivotally mounted upon said pin 22 is a handle 23 which has a free movement to swing on the pivot, for a purpose hereinafter more fully set forth. The outwardly depressed portion 5 of the plate 4 is provided at its upper right hand end with an outwardly extending lug 24 which limits the movement of the latch 8 to the right, as fully shown in Figure 2 of the drawings. The object of the segmental groove 18 is to allow the member 14 to have a complete half turn so that the handle 23 can always be swung downwardly and always remain in a vertical position.

In operation, it will be seen that the latch being in the position shown in Figure 2 of the drawings, and handle 23 is moved in the direction of the arrow, and the pin 19 travels in the segmental groove 18 of the latch 8 until it strikes the end of the segmental groove, and the latch is then carried by the plate 14 downwardly into the keeper 10, and the beveled face 11 of the hooked end 9 engaging the curved wall 12 of the keeper, tightly draws the door against the jam. When the latch is in this position the handle is in an upward vertical position as shown in dotted lines, Figure 119.

- 1, and the handle is then swung downwardly on its pivot 22 to the position shown in full lines, Figure 1. In the event that the door slides in the reverse direction from that shown in the drawings, the latch is inverted and likewise the keeper is inverted, and the latch works in an upward direction to latch the door, and in a downward direction to release the door.
- 10 The slot 17 in the latch 8 is adapted to receive a pad lock 25 which engages the raised portion 5 of the attaching plate, and prevents the movement of the latch and thus the latch serves as a lock to prevent the opening of the door.

Having thus fully described my invention what I claim is:

- 20 1. A latch of the character described comprising an attaching member, a stub shaft carried thereby, a latch pivoted on said stub shaft, and a member pivotally mounted on the stub shaft, and having a lost motion connection with the latch, and a handle pivotally mounted on the member whereby the handle is at all times maintained in a downward vertical direction.

- 30 2. A latch of the character described comprising an attaching plate, a stub shaft carried thereby, a latch pivotally mounted on said stub shaft, and having a segmental slot, a member pivotally mounted on the stub shaft, a pin carried by the member and extending into the segmental slot, and a handle mounted on the member at right angles to the stub shaft, whereby the handle is maintained in a downward position when the latch is latched or unlatched.

- 40 3. A latch of the character described comprising an attaching plate, a stub shaft mounted thereon, a latch pivotally mounted on the stub shaft intermediate its ends, and having at one end a hook to cooperate with the keeper and the opposite end provided with a slot to receive a lock which engages the attaching plate for preventing the movement of the latch, and a member pivotally mounted on the stub shaft and having a lost motion connection with the latch, and a pivoted handle carried by the member, whereby the handle is swung downwardly when the latch is latched or unlatched.

- 50 4. A latch of the character described comprising an attaching plate having a raised central portion, a stub shaft carried by said raised central portion, a latch pivotally mounted intermediate its ends on the stub shaft, a hook carried by one end of the latch, and the opposite end having a slot adapted to receive a pad lock which cooperates with the raised portion of the attaching plate to prevent the movement of the latch, a member pivotally carried by the stub shaft and having a lost motion

connection with the latch, and a handle pivotally mounted on a horizontal pin carried by the member, whereby the handle is always maintained in a downward position.

65 5. A latch of the character described comprising an attaching plate, a stub shaft carried by the attaching plate, a latch pivoted intermediate its ends on the stub shaft, and having a hook at one end, and a slot at the opposite end adapted to receive a pad lock to engage the attaching plate to prevent the movement of the latch, a member pivotally mounted on the stub shaft, and having a lost motion connection with the latch for swinging the same into and out of a latched position, and a handle pivotally mounted on a horizontal pivot carried by the member, whereby the handle is at all times maintained in a downward direction.

70 6. A latch of the character described comprising an attaching plate, a stub shaft carried thereby, a latch pivoted intermediate its end on the stub shaft, and having a hook at one end and a slot at the opposite end to receive a pad lock to engage the attaching plate and prevent the movement of the latch, a stop for limiting the movement of the latch, a member carried by the stub shaft, a pin and slot connection between the latch and the member, and a handle pivotally mounted upon the member, whereby the handle is at all times maintained in a downward position.

75 7. A latch of the character described comprising an attaching plate, a stub shaft carried by the plate, a latch pivotally mounted on the stub shaft, a member pivotally mounted on the stub shaft, a pin and slot connection between the latch and the member, and a handle pivotally mounted upon the member on a horizontal pivot, whereby the handle is always maintained in a downward position to prevent the movement of the latch when in a latched or unlatched position.

80 8. A latch of the character described comprising an attaching plate, having a raised central portion, a stub shaft carried thereby, a latch pivoted intermediate its ends on the stub shaft, and having a hook at one end and a slot at the opposite end adapted to receive a pad lock to engage the raised portion of the attaching plate to prevent the movement of the latch, a member pivotally mounted on the stub shaft, and a pin and slot connection between the latch and the member, and a handle pivotally mounted on the member, whereby the same is at all times maintained in a downward direction.

85 In testimony whereof, I have signed this specification:

PHILIP LANG,
